Fig. 3

Fig. 4

FIGURE 1 is a perspective view of a male connector bar for modular terminal block showing my new design; FIGURE 2 is a top plan view of the conductor bar shown in FIGURE 1;

FIGURE 3 is a side elevational view of the same; and FIGURE 4 is an end view in elevation of the same.

I claim:

The ornamental design for a male connector bar for modular terminal blocks, as shown and described.
